Primary Examiner — Mojtaba Tehrani*(74) Attorney, Agent, or Firm* — Crowell & Moring LLP(57) **CLAIM**

We claim the ornamental design for a medical refrigerator, as shown and described.

DESCRIPTION

FIG. 1 is a perspective view of a medical refrigerator of the present invention;
FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is an enlarged view of a bottom part thereof delineated by a dash-dot line shown in FIG. 1.

The even broken lines show parts of the medical refrigerator that represent unclaimed subject matter and form no part of the claimed design. The dash-dot broken lines in FIG. 1 drawing depict boundaries of the enlarged view shown in FIG. 8 only and form no part of the claimed design.
